UNITED STATES PATENT OFFICE.

RAY C. NEWHOUSE, OF MILWAUKEE, WISCONSIN, ASSIGNOR TO ALLIS-CHALMERS
MANUFACTURING COMPANY, OF MILWAUKEE, WISCONSIN, A CORPORATION OF
DELAWARE.

GRINDING-MILL AND TUMBLING COMMINUTING-BODY THEREFOR.

1,331,964.

Specification of Letters Patent. Patented Feb. 24, 1920.

Application filed April 29, 1915. Serial No. 25,327.

To all whom it may concern:

Be it known that I, RAY C. NEWHOUSE, a citizen of the United States, residing at Milwaukee, in the county of Milwaukee and State of Wisconsin, have invented a certain new and useful Improvement in Grinding-Mills and Tumbling Comminuting-Bodies Therefor, of which the following is a specification.

10 This invention relates to improvements in the construction of comminuting or grinding mills for rock, ore and similar materials, and particularly to an improved form of comminuting body adapted for use 15 in such mills.

An object of the invention is to provide a comminuting or grinding mill which is simple in construction and efficient in operation. Another object is to provide a grinding 20 body of such form that it will tend to engage similarly formed adjacent grinding bodies in the mill along surfaces instead of lines and points, thereby enhancing the comminuting effect upon the material. One of 25 the more specific objects is to provide a plurality of grinding bodies having spherical zone surfaces adapted for coaction with surfaces of adjacent similarly formed grinding bodies.

30 It has been customary in the prior art to employ several types of grinding bodies in comminuting mills of the tube and ball types. With the use of the ordinary flint pebbles and of iron spheres or balls, it has been found that there is ordinarily only 35 point coaction between the adjacent elements, thus eliminating the desirable comminuting effect which results from surface coaction. The spherical form of grinding

40 body is however desirable because of its ability to roll in any direction, thus tending to evenly distribute the wear. With grinding bodies of cylindrical or rectangular prismatic forms the coaction is usually along 45 a line and may sometimes be along adjacent surfaces, but the inability of such bodies to roll universally, makes it difficult to readily secure surface coaction. The grinding bodies of the present invention are prefer-

50 ably formed with spherical outer zone surfaces so that the universal rolling and uniform wearing effect is maintained, while the surface coaction is secured by providing spherical concave end surfaces adapted for

coaction with the outer zone surfaces of adjacent grinding bodies. 55

A clear conception of an embodiment of the invention may be had by referring to the drawing accompanying and forming a part of this specification in which like reference 60 characters designate the same or similar parts in the various views.

Figure 1 is a front view of a comminuting or grinding body.

Fig. 2 is an end view of a comminuting 65 or grinding body.

Fig. 3 is a fragmentary sectional view through a mass comprising a number of comminuting bodies and material being ground thereby. 70

Fig. 4 is a diagrammatic disclosure of a tube mill having the invention applied therein.

Fig. 5 is a front view of a modified form of comminuting or grinding body. 75

Fig. 6 is an end view of the form of grinding body disclosed in Fig. 5.

Fig. 7 is a central vertical section through another form of comminuting or grinding body. 80

Fig. 8 is an end view of the form of comminuting or grinding body disclosed in Fig. 7.

Each of the comminuting or grinding bodies 1, see Figs. 1 and 2, is formed preferably of chilled cast iron or other very hard material, and has an outer spherical zone surface 2. The ends of each of the bodies 1 are formed concave, having spherical surfaces 3 which are formed with generating radii equal to the radius of generation of the adjoining surface 2. 85

When the grinding bodies 1 are placed within a mill grinding chamber, they assume various positions as indicated in Fig. 95 3, the outer zone surfaces 2 of some of the bodies having surface coaction with the concave surfaces 3 of adjacent bodies. As the mill is rotated, the adjacent bodies roll or slide relatively to each other at the coacting 100 surfaces and tend to reduce the material 4 between the relatively moving bodies to a fine powder.

It will be noted that by forming the grinding bodies 1 with spherical zone surfaces 2, 3, having equal radii, the maximum rolling effect and uniform wear are secured, 105 while the desirable surface coaction with

adjacent bodies is also maintained. The grinding bodies of the present invention may readily be formed of any desirable size and material by casting or with the use 5 of dies, and can be very cheaply constructed.

While the grinding bodies 1 of Figs. 1, 2 and 3 are disclosed as having spherical surfaces 2, 3, it will be apparent that these surfaces may be cylindrical as disclosed in 10 Figs. 5 and 6 so long as the desired surface coaction is obtainable. The bodies 1 may also be used in a mill in combination with spherical bodies having no concavities, or they may be formed with more than two 15 concave surfaces 3 as disclosed in Figs. 7 and 8 and used in combination with spherical bodies.

It should be understood that it is not desired to be limited to the exact details of 20 construction shown and described, for obvious modifications will occur to a person skilled in the art.

It is claimed and desired to secure by Letters Patent,—

25 1. As an article of manufacture, a universally tumbling comminuting body having a continuous convex outer surface, and having a recess bounded by a concave outer surface, the curvature of concavity being substantially equal to the curvature of convexity.

2. As an article of manufacture, a comminuting body having a portion bounded by a continuous convex surface, and having a 35 pair of oppositely disposed recesses in other portions thereof bounded by curved concave surfaces.

3. As an article of manufacture, a comminuting body having a continuous curved 40 convex surface, and a curved concave surface having a generating radius substantially equal to that of said convex surface.

4. As an article of manufacture, a comminuting body having a continuous curved 45 convex surface, and a pair of oppositely disposed concave surfaces, all of said surfaces having substantially equal generating radii.

5. As an article of manufacture, a comminuting body having a substantially 50 spherical outer zone surface and having a substantially spherical concave surface at one portion thereof.

6. As an article of manufacture, a comminuting body having a substantially 55 spherical outer zone surface and having a plurality of oppositely disposed spherical concave surfaces thereon.

7. As an article of manufacture, a tumbling comminuting body having a substantially 60 spherical concave outer surface at one portion thereof.

8. In combination, a comminuting mill, and a plurality of tumbling grinding bodies 65 therein free to move in any direction, one of said bodies being formed with an inwardly

curved outer surface and another of said bodies being formed with an outwardly curved outer surface and said surfaces being adapted for mutual coaction.

9. In combination, a comminuting mill, a 70 universally tumbling comminuting body in said mill having salient and reentrant outer surface portions, and a second universally tumbling comminuting body in said mill having salient and reentrant outer surface 75 portions adapted for coaction with complementary surface portions of said first mentioned body, said coaction constituting at least line contact throughout said coacting portions.

10. In combination, a comminuting mill, a tumbling comminuting body in said mill free to move in any direction and having an outer salient surface of revolution, and a second tumbling comminuting body in said 85 mill free to move in any direction and having an outer surface of revolution at least one portion of which is reentrant, said bodies at surfaces being adapted for mutual coaction.

90 11. In combination, a comminuting mill, a universally tumbling comminuting body in said mill having a cross section comprising enlarged end portions and a contracted connecting portion, and a second tumbling comminuting body in said mill universally movable independently of said first mentioned body and having portions adapted 95 for coaction with complementary portions of said first mentioned body.

100 12. In combination, a comminuting mill, a universally tumbling comminuting body in said mill having a cross section bounded at its ends by a convex curved line and at an intermediate portion by concave curved 105 lines located on opposite sides of the section, and a section tumbling comminuting body in said mill universally movable independently of said first mentioned body and having a portion adapted for coaction with said intermediate portion of said first mentioned body.

110 13. In combination, a comminuting mill, a universally tumbling comminuting body in said mill comprising a body of revolution 115 having a cross section bounded at an end portion by outwardly curved lines and at a medial portion by inwardly curved lines, and a second tumbling comminuting body in said mill universally movable independently of said first mentioned body and having a portion adapted for coaction with said medial portion of said first mentioned body.

120 14. In combination, a comminuting mill, a universally tumbling comminuting body 125 in said mill bounded by an outer surface the contour of at least one section of which is reentrant, and a second tumbling comminuting body in said mill universally movable independently of said first mentioned body 130

and having a salient surface adapted for coaction with said reentrant section of said first mentioned body.

15. In combination, a comminuting mill, 5 a universally tumbling comminuting body in said mill having a shape described by rotating on an axis a plane figure enlarged at an end portion and reduced at an intermediate portion, and a second tumbling com-

minuting body in said mill universally movable independently of said first mentioned body and having a portion adapted for coaction with said reduced intermediate portion of said first mentioned body. 10

In testimony whereof the signature of the 15 inventor is affixed hereto.

RAY C. NEWHOUSE.

It is hereby certified that in Letters Patent No. 1,331,964, granted February 24, 1920, upon the application of Ray C. Newhouse, of Milwaukee, Wisconsin, for an improvement in "Grinding-Mills and Tumbling Comminuting-Bodies Therefor," errors appear in the printed specification requiring correction as follows: Page 2, line 89, claim 10, before the word "surfaces" insert the word *said*; same page, line 107, claim 12, for the word "section" read *second*; and that the said Letters Patent should be read with these corrections therein that the same may conform to the record of the case in the Patent Office.

Signed and sealed this 30th day of March, A. D., 1920.

[SEAL.]

M. H. COULSTON,
Acting Commissioner of Patents.
